A. G. KARKAU,
IMPULSE STARTER.
APPLICATION FILED MAR. 15, 1916.

1,264,086.

Patented Apr. 23, 1918.

UNITED STATES PATENT OFFICE.

ALBERT G. KARKAU, OF CLEVELAND, OHIO, ASSIGNOR TO THE K. W. IGNITION COMPANY, OF CLEVELAND, OHIO, A CORPORATION OF OHIO.

IMPULSE-STARTER.

1,264,086.

Specification of Letters Patent. Patented Apr. 23, 1918.

Application filed March 15, 1916. Serial No. 84,288.

To all whom it may concern:

Be it known that I, ALBERT G. KARKAU, a citizen of the United States, residing at Cleveland, in the county of Cuyahoga and 5 State of Ohio, have invented a certain new and useful Improvement in Impulse-Starters, of which the following is a full, clear, and exact description.

This invention relates to what may be 10 termed an "impulse starting mechanism" for use in connection with a magneto, as a part of the ignition system for a fluid fuel engine. Through the instrumentality of this mechanism, when the engine is turned over 15 in the ordinary manner, the magneto shaft will be compelled to give one or more accelerated rotations that will result in the production of a series of sparks in the engine cylinders, and when this has been 20 accomplished and the engine started, the starting mechanism will be rendered ineffective and after that the magneto will run regularly in its proper and predetermined relationship with respect to the engine.

25 The object of the invention is to produce a device as above mentioned, in which the various instrumentalities are of simple form and so arranged as to efficiently operate.

Generally speaking, the invention may be 30 said to comprise the elements and combinations thereof set forth in the accompanying claims.

Reference should be had to the accompanying drawings forming a part of this 35 specification, in which Figure 1 is a front elevation, with parts in section, of a portion of a magneto showing the device of this invention in connection therewith; Fig. 2 is a front elevation of certain parts of the operating mechanism of the device of this invention; Fig. 3 is a side elevation of the showing in Fig. 2; and Fig. 4 is a sectional elevation of the showing in Fig. 3.

Referring to the drawings, 1 represents 45 the end plate of the housing of the magneto, and in this end plate there is mounted a suitable bearing member 2 in which is journaled the shaft 3; upon which shaft is mounted the armature of the magneto. Se- 50 cured to the shaft is a hub 4 having a disk 5 formed integral therewith or secured thereto. Surrounding the hub 4 is a driving member 6. This member is provided with a portion which fits upon the hub 4 55 but is not secured thereto, and is formed

with an annular recess, as indicated at 7. The inner end of the recessed portion is open and the inner portion of the driving member 6 is close to the disk 5. Within the recessed portion 7 there is a coil spring generally 60 represented at 8 which spring is substantially annular and at one end abuts against a pin 9 which pin is carried by the driving member 6. This pin 9 extends through the driving member 6 and across the recessed 65 portion 7 of the driving member 6. At its opposite end the spring 8 abuts against a pin 10, which pin extends across the recessed portion 7 and is carried by the disk 5. The pins 9 and 10 are spaced from each 70 other and between the pins there is a coil spring 11.

Upon the periphery of the disk 5 there are one or more notches, such as indicated at 12, these notches being formed with a 75 slanting bottom surface and a substantially flat wall slightly undercut.

Upon the outer surface of the driving member 6 there are formed projections or striker members 13, these projections having 80 slanting sides, as indicated more particularly in Fig. 3.

Upon the end plate 1 of the magneto casting there are outwardly extending parts 15 which are adapted to support the opposite 85 ends of a bracket 16. This bracket has an upwardly extending portion 17 with a forwardly extending ledge 18. The ledge 18 supports a housing 19 in which is a plunger 20. This plunger 20 has a head 21 which 90 extends within an enlarged portion 22 of the housing 19. The plunger is hollow and within the plunger there is a spring 23 which at its upper end engages with the top of the housing 19. The housing 19 is threaded 95 through a suitable opening in the forwardly extending ledge 18 so that it may be adjusted with respect to this ledge.

Suitably pivoted upon one of the posts 15 is a latch 24. This latch has an arm 25 by 100 which the latch may be moved under certain conditions which will be later described. The top of the latch is provided with a table-like portion 26 and with this table portion the plunger 20 is adapted to contact. The latch 24 is provided with a nose 105 27 which is more or less pointed and is adapted to engage with a recessed part 28 formed by an extending portion 28a of a pawl 29. This pawl is pivotally mounted 110

upon the other post 15 and is so mounted that its weight tends to cause it to drop downwardly. The latch 24 overlies the pawl 29 and the movement of the pawl raises 5 the latch and when it raises it sufficiently the nose of the latch catches the recessed portion 28 of pawl 29. The pawl 29 is provided with a toe 30 which in one position is adapted to engage with the periphery of the 10 disk 5 and as this disk turns it engages with a notch 12, and thus stops rotation of shaft 3. The pawl extends beyond the edge of the disk 5 which is toward the member 6 and therefore is in the path of movement 15 of the striker members carried by the member 6.

The operation of the device is as follows: The engine is assumed to be not running, and the pawl in the position shown in Fig. 20 1, the arm 25 of the latch 24 is depressed, thereby raising the latch 24 until the nose is moved out of the recessed portion 28 of the pawl 29, thus permitting the pawl 29 to drop and engage with the periphery of 25 the disk 5, as shown in Fig. 2.

The engine is turned over as usual, whereupon the member 6, which will be suitably connected with the crank shaft of the engine in connection with which the magneto is 30 used, is caused to turn and the disk 5 will likewise be caused to turn, as the spring 8 forms a driving connection between the member 6 and the disk 5. The members 5 and 6 will turn together until the pawl 29 35 engages with one of the notches 12 which will prevent further turning of the disk 5, but the member 6 will continue to turn. Under these circumstances, as the driving member 6 is further turned, it will cause a 40 compression of the spring 8, for the pin 10 forms a fixed stop and when the driving member 6 has sufficiently turned so that one of the striker members 13 engages with the pawl 29, it will knock the pawl out of engagement with the particular notch 12 of the disk 5 with which it has been in engagement, and the disk 5 thus being free to turn 45 will be driven forward very quickly under the expanding action of the spring 8. This 50 will cause a rapid turning of the magneto shaft 3 and cause a rapid series of sparks in the engine cylinder and thus effect an easy starting. The spring 11 which lies between the pins 9 and 10, serves as a buffer when the 55 disk 5 is released and the pins 9 and 10 approach each other.

If the turning action of the member 6 has been sufficiently rapid so as to impart a stiff blow to the pawl 29, it will throw the pawl 60 29 sufficiently far outwardly so that the nose of the latch 24 will be moved beyond the recessed portion 28 of the pawl 29 and the pawl 29 will be stopped by the engagement of the nose of the latch as it engages in recess 26, as the pawl drops back, thus hold-

ing the pawl out of further engagement with the notches 12 in a disk 5.

If the blow imparted to the pawl 29 by one of the cam portions 13 has not been sufficiently hard to throw the pawl far enough 70 outwardly for the latch 24 to engage with the pawl, the pawl 29 will be in position to engage with a succeeding notch 12 upon the disk 5, and the operation which has previously been described will be repeated, thus 75 producing a further succession of sparks in the engine cylinder or cylinders. Of course, it will be understood that as soon as the engine has started the rotation of the driving member 6 will be sufficiently rapid to impart the necessary blow to the pawl 29 to cause the latch 24 to engage it. Therefore, under normal running conditions of the engine the pawl 29 will be held by the latch 24. 80

The housing 19 is adjustable with respect 85 to the ledge 18 and by adjustment the pressure of plunger 20 upon the latch 24 may be varied, thereby affording a means of regulation for determining the engine speed at which the pawl 29 will be struck sufficiently 90 to lift the latch 24 and cause it to engage.

Having described my invention, I claim:

1. The combination with an armature shaft of a magneto, a driving member therefor, a resilient member forming a driving connection between said shaft and driving member, a stop means for said shaft including a pivoted pawl, means operated by the driving member for engaging the pawl and disconnecting the stop means from engagement, a latch oppositely pivoted with respect to the pawl and extending toward the pawl, said latch having a portion adapted to engage with the pawl when the stop means is thrown out of engagement. 100

2. The combination with an armature shaft of a magneto, a driving member therefor, a resilient member forming a driving connection between the said shaft and driving member, a locking device for said shaft comprising a pivoted pawl adapted to engage in a notch, a member carried by the driving member adapted to engage the pawl and throw it out of engagement with said notch, a latch oppositely pivoted with respect to the pawl, said latch extending toward the pawl and adapted to engage with a recessed portion of the pawl when the pawl is thrown out sufficiently far, and means for normally pressing the latch into 110 a position to engage with the pawl. 115

3. The combination with an armature shaft of a magneto, a driving member therefor, a resilient member forming a driving connection between the said shaft and driving member, said driving member being formed with a notch, a pawl pivoted adjacent the driving member, said pawl extending above the driving member and adapted to engage with the said notch, a 125 120

- member carried by the driving member adapted to engage the pawl and throw it out of engagement with said notch, a latch pivoted oppositely to the pawl, said latch extending above the pawl, the pawl being formed with a recess and the latch being formed with a nose which is adapted to engage with the recess in the latch when the latch is thrown out sufficiently far, and means for normally pressing the latch into a position to engage with the pawl.
4. The combination with an armature shaft of a magneto, a driving member therefor, a coil spring interposed between the shaft and said driving member, said coil spring being in compressing relation with respect to the shaft and driving member to form a driving connection between the same, a locking device for said shaft, means operated by the driving member for throwing the locking device out of engagement, and a latch extending over said locking device, said latch being adapted to engage with the locking device for holding the same when the locking device is thrown out of engagement.
5. The combination with an armature shaft of a magneto, a driving member therefor, a stop member carried by the driving member and a stop member associated with the shaft, a resilient member lying between the said stop members, said resilient member being compressed as the driving member drives the armature shaft, thereby forming a driving connection, a locking device for said shaft, means operated by the driving member for throwing the locking means out of engagement, and a latch extending over the said locking device, said latch being provided with a nose adapted to engage a recessed portion in the locking device when the locking device is thrown out of engagement.
6. The combination with an armature shaft of a magneto, a driving member therefor, a stop member carried by the driving member, and a stop member associated with the shaft, a coil spring lying between said members, the ends of said coil spring engaging with the said stop members whereby the coil spring will be compressed as the driving member is driven, the said coil spring forming a driving connection between the shaft and driving member, a locking device for said shaft, means operated by the driving member for throwing the locking means out of engagement, and a latch extending over said locking device, said latch being provided with a nose adapted to engage a recessed portion in the locking device when the locking device is thrown out of engagement.
7. In combination with the shaft of a magneto, a driving member therefor, a resilient member forming a driving connection between the said shaft and the driving member, a notched disk associated with the armature shaft, a striker member associated with the driving member, a pawl adapted to engage with the periphery of the notched disk and extending beyond the side of the said disk into the path of movement of the said striker member, an extending portion upon the pawl forming a recess upon the pawl, a pivoted latch member having a nose which nose extends above the projecting portion of the pawl, when the pawl is in engagement with the periphery of the notched disk and which nose is adapted to engage beneath the extending portion when the pawl is thrown outwardly by the striker member, the said latch being provided with a ledge, a spring-pressed plunger adapted to engage with the ledge, thereby normally urging the latch toward the pawl.
8. The combination with a magneto shaft of a driven member, a resilient member forming a driving connection between the shaft and driving member, a notched disk associated with the shaft, a striker member associated with the driving member, a pivoted pawl member adapted to engage with the periphery of the notched disk, a pawl member extending beyond the side of the disk and the path of movement of the striker member, said pawl having a portion extending therefrom, a pivoted latch member having a nose adapted to engage beneath the extending portion upon the pawl when the pawl is thrown outwardly by the striker member, a bracket supported from the magneto, a spring-pressed plunger adjustably carried upon said bracket, said plunger engaging with a portion of the latch member to normally urge the latch member toward the pawl.
9. The combination with an armature shaft of a magneto, of a driving member, a resilient means operatively connecting the shaft to the driving member, a stop device for said shaft comprising a notched member associated with the shaft, a pivoted pawl having a toe the pawl extending in a direction opposite to the direction of rotation of the armature shaft, said pawl also having a recessed portion, a pivoted latch said latch having a nose which extends toward the pawl the nose of said latch being adapted to engage in the recessed portion of the pawl when the pawl is thrown out sufficiently far, and means carried by the driving member adapted to engage the pawl and throw it out of engagement with the notched member.
10. In a magneto driving device, a magneto shaft, a driving member therefor, an annular chamber surrounding the shaft, stop members extending into the chamber and carried respectively by the shaft and driving member, a coil spring extending through the major portion of said annular chamber and engaging the stop members and adapted to

- be compressed by the movement of the driving member relative to the shaft, relatively short coiled buffer springs between the stop members and occupying the remainder of the chamber not occupied by the first named spring, a locking device for said shaft, means operated by the driving member for throwing the locking device out of engagement, and a latch coöperating with the locking device said latch being adapted to engage with the locking device for holding the same when the locking device is thrown out of engagement.
11. In a magneto driving device, a magneto shaft, a driving member therefor, an annular chamber surrounding the shaft, stop members extending into the chamber and carried respectively by the shaft and driving member, a coil spring extending through the major portion of said annular chamber and engaging the stop members and adapted to be compressed by the movement of the driving member relative to the shaft, relatively short coiled buffer springs between the stop members and occupying the remainder of the chamber not occupied by the first named spring, a stop means for said shaft including a pivoted pawl, means operated by the driving member for engaging the pawl and disengaging the stop means from engagement, a latch oppositely pivoted with respect to the pawl and extending toward the pawl said pawl having a portion adapted to engage with the latch when the stop means are out of engagement.
12. In a magneto driving device, a magneto shaft, a driving member therefor, an annular chamber surrounding the shaft, stop members extending into the chamber and carried respectively by the shaft and driving member, a coil spring extending through the major portion of said annular chamber and engaging the stop members and adapted to be compressed by the movement of the driving member relative to the shaft, relatively short coiled buffer springs between the stop members and occupying the remainder of the chamber not occupied by the first named spring, a stop means for said shaft including a pivoted pawl, means operated by the driving member for engaging the pawl and disengaging the stop means from engagement, a latch oppositely pivoted with respect to the pawl and extending toward the pawl said pawl having a portion adapted to engage with the latch when the stop means are out of engagement.

In testimony whereof, I hereunto affix my signature.

ALBERT G. KARKAU.
